CONTAINER FOR AND METHOD OF WRAPPING IRREGULAR OBJECTS

Harold Amatel, Glendale, N. Y., assignor to Westinghouse Electric Corporation, East Pittsburgh, Pa., a corporation of Pennsylvania

Application August 5, 1943, Serial No. 497,422

10 Claims. (Cl. 206—46)

1

This invention relates to containers for holding fragile irregular objects, whereby they may be shipped without danger of breakage.

The primary object of my invention, generally considered, is a shipping container for irregular objects, notable examples of which are magnetrons, which container is light in weight yet strong and capable of holding any fragile portions of the object away from the outer walls to thereby prevent breakage or other damage thereto.

Another object of my invention is to provide a container for irregular objects, such as those including a generally cylindrical portion with lateral projections, said container comprising a cradle device socketed to partially enclose the generally cylindrical body portion as well as support the lateral projections and prevent undesired shifting, while allowing rotation of said cylindrical portion without removal.

A further object of my invention is to provide a container for irregular objects, such as magnetrons, which container includes a socket holding the body of the object so that it does not come in contact with the outer walls, said socket also serving to lock the object in place agains undesired shifting.

A still further object of my invention is to provide a container for irregular objects, which container includes a plurality of telescoping hollow parts and a central supporting member for holding the object in place on said supporting member, whereby said object may be removed by bodily lifting out of the supporting cradle without unscrewing or untying any parts.

An additional object of my invention is a container including six main parts which telescope with respect to one another to make a strong closure for the protection of an irregular object such as a magnetron.

Another object of my invention is to provide a container for so holding a magnetron that a protective tube placed over the output lead may be removed without taking the object out of the cradle of the container so that, for example, plumbing may be connected or disconnected, with the container acting as a jig.

A further object of my invention is a container, for holding a magnetron comprising a generally cylindrical portion with members projecting laterally therefrom at an angle to one another, said container comprising a cradle holding said cylindrical portion in such a way that the projecting members may be tilted, as to facilitate connection

2

with plumbing or the like, without removal from the container.

Other objects and advantages of the invention, relating to the particular arrangement and construction of the various parts, will become apparent as the description proceeds.

Referring to the drawings:

Fig. 1 is a perspective of one embodiment of my container after all the parts have been assembled.

Fig. 2 is an exploded view in perspective of the object to be enclosed and four inner parts of the container, indicating the manner in which said object and the container parts fit together.

Fig. 3 is an exploded perspective, on the same scale as Fig. 2, indicating the manner in which the fifth and sixth container parts are put together.

Fig. 4 is a sectional view on the normally vertical longitudinal mid-plane of the assembled enclosed object and container, as indicated by the line IV—IV of Fig. 5, in the direction of the arrows, the object being shown in elevation.

Fig. 5 is a transverse sectional view on the line V—V of Fig. 4, in the direction of the arrows.

Fig. 1^a is a view corresponding to Fig. 1 but showing another embodiment of my invention.

Fig. 2^a is an exploded perspective view indicating how the first three parts of the container of Fig. 1^a fit together for holding an object such as a magnetron.

Fig. 3^a is an exploded perspective view, to the same scale as Fig. 2^a, showing how parts #4, #5 and #6 of the container of Fig. 1^a fit together in completing the enclosure of a magnetron.

Fig. 4^a is a sectional view on the normally vertical longitudinal mid-plane of the container illustrated in Fig. 1^a, as viewed in the direction of the arrows on the line IV^a—IV^a of Fig. 5^a, the enclosed magnetron being shown in elevation.

Fig. 5^a is a transverse sectional view on the line V^a—V^a of Fig. 4^a, in the direction of the arrows.

Fig. 1^b is a perspective of a container involving another embodiment of my invention.

Fig. 2^b is an exploded perspective view of the first three main parts of the container of Fig. 1^b, indicating how they go together and how an enclosed magnetron fits in place with respect thereto.

Fig. 3^b is an exploded view of parts #4, #5 and #6 of the embodiment of Fig. 1^b, showing how said parts fit together to complete the enclosure of the magnetron.

Fig. 4^b is a sectional view on the normally vertical longitudinal mid-plane of the container

shown in Fig. 1^b, as viewed in the direction of the arrows on the line IV^b—IV^b of Fig. 5^b, the enclosed magnetron being illustrated in elevation.

Fig. 5^b is a transverse sectional view on the line V^b—V^b of Fig. 4^b, in the direction of the arrows, the enclosed magnetron being indicated in dotted lines.

Referring to the drawing in detail, and first considering the embodiment of my invention illustrated in Figs. 1 to 5, inclusive, there is shown a magnetron 10 comprising a generally cylindrical body or anode portion 11 from which fins 12 project for cooling purposes, side plates 13, which are generally circular below the mid-horizontal plane, except for notches where the cathode leads extend into the body portion, and generally rectangular thereabove, and a connecting top plate 14 for said side plates. In the present embodiment, the output connection 15 extends generally in line with the cathode leads 16 and 17, that is, all lie in the normally horizontal plane through the center of the body portion 11. The glass enclosure 18, through which the cathode lead 17 extends, is shown as tipped off at 19.

In order to efficiently and economically enclose the object, such as the magnetron 10, in a container light in weight, while at the same time safely protecting the delicate parts such, for example, as the glass and tubes 18 and the cathode leads 16 and 17 projecting therefrom, I desirably form the six parts of the container of corrugated cardboard, rather than of wood or other material. I do not, however, wish to be limited to the use of such material, as wood could be used if considered more desirable, although it would weigh and cost more.

Part #1 of the container, generally designated by the reference character 20, is preferably formed from a rectangular piece 21 of corrugated cardboard by bending it to U shape, that is with three panels with right angles therebetween as shown in Fig. 2, so as to snugly embrace the body 11 of the magnetron, form the primary member of a cradle therefor, and have its side panels lie flat against the side plates 13 and ends of the anode portion 11. The magnetron is supported by its top plate 14 engaging the top edges 22 and 23 of the U-shaped member 21. The bottom panel 24 of the U-shaped member is of an interior width corresponding with the axial length of the cylindrical portion 11.

Part #2 of the container is preferably formed from a relatively long flat rectangular piece of corrugated cardboard 25 by cutting a central rectangular aperture 26 therein while flat and of such a size that it snugly receives part #1 and the embraced magnetron 10, forming the secondary member of a cradle therefor. The portions of said cardboard 25 beyond the ends of the slot 26 are then bent at right angles downwardly, inwardly, and upwardly making side panels 27, bottom panels 28 and side panels 29 forming with the remainder or top panel 40, hollow open-end box portions, the side panels 29 of which snugly engage the side edges of the side plates of part #1.

Part #3 of my container is preferably formed from a rectangular piece of corrugated cardboard 30 by bending the end portions at right angles upwardly to leave a center panel 31, and form side panels 32. It is then bent inwardly at right angles to provide shoulder or top portions 33, leaving a space therebetween to snugly receive the side panels of part #1, then downwardly at right

angles to provide inner side panels 34, and at a point corresponding with the height of the side panels 27 of part #2, the end portions are bent outwardly at right angles to provide inner bracing panels 35, and of such a width that they normally engage the inner surfaces of the panels 32. When said panels 32 are vertical, the inner panels 34 are also vertical and spaced to snugly engage the side panels of member #1, while the bracing panels 35 rest on the top panel 40 of the part #2.

It will, therefore, be seen that the magnetron is first fitted in part #1, then the enclosed parts thereof are fitted in part #2, with the tip 19 received in opening 36 in top panel 40 of said part, and the assembled parts are then embraced between the inner panels 34, bottom panel 31 and reinforcing panels 35 of part #3.

After the foregoing assembly has been effected, part #4, preferably consisting of a rectangular corrugated cardboard member 37, is placed beneath part #3 and the end portions bent at right angles around it and the parts assembled therewith, providing closing panel 38, for the opening in part #3 illustrated at the left thereof, and panel 39 closing the opening at the other end thereof. Top panels 41 and 42 close the remainder of the top of part #3, or that not closed by the top plate 14 of the magnetron 10. The adjacent edges 43 and 44 of said top panels 41 and 42 extend into snug engagement with the edges 45 and 46, respectively, of the top plate 14 of said magnetron.

Referring now to Fig. 3, it will be seen that, after fitting part #4 about the assembled first three parts and the magnetron, part #5, formed as a rectangular preferably corrugated cardboard box device 47 open at top and bottom, is telescoped over part #4, and the parts associated therewith. Part #5 is formed from a rectangular piece of material by bending four panels thereof into right angular relationship and securing the opposite ends together as by means of glued cloth 50.

Part #6 is also a rectangular preferably corrugated cardboard box 48, formed generally like member 47 and held in position, after bending its panels into right angular relationship, by a strip of glued cloth 53, but with a pair of opposite ends, rather than top and bottom, open. The area of each open end corresponds with the area of each end panel, 49 or 51, of part #5, so that part #6 snugly telescopes over part #5 and the associated parts, completing the enclosure of the magnetron.

A consideration of Figs. 4 and 5 will show that the magnetron illustrated, as completely enclosed in the six parts, engages the outer part #6 only at its upper or supporting plate 14, all of the other parts being spaced from the sides and ends. That is, there is considerable air space between the cylindrical body portion and the bottom of the container, as well as between the ends of the parts 15, 16 and 17 and the ends of said container. It will also be seen from a consideration of these figures that there are from two to four thicknesses of corrugated cardboard protecting every part of the device against breakage, except the upper supporting plate 14 of the magnetron, which is thick and adapted to withstand relatively severe shocks.

It will also be seen that by virtue of the panels 41 and 42 engaging the edges 45 and 46 of the top plate 14, longitudinal shifting of the magnetron in the container is prevented, even without auxiliary fastening means. In the same way, by

virtue of the magnetron body, after housing in member #1, fitting in the slot 26 in part #2, lateral shifting in the container is prevented. Of course, up and down shifting of the magnetron in the container is also prevented by the direct engagement of the top of the supporting plate 14 with the upper wall 52 of the outer housing member 48, and the projecting side portion of this plate 14 resting on the top panels 33 of part #3. However, by virtue of the spacing of the projecting parts 15, 16 and 17 above the top panel 49 of part #2, a limited amount of tilting of the magnetron with respect to said part is permitted, even without complete removal of the magnetron from the container.

Referring now to the embodiment of my invention illustrated in Figs. 1^a to 5^a, inclusive, there is shown a magnetron 60 comprising a generally cylindrical body or anode portion 61 from which fins 62 project for cooling purposes. In the present embodiment, there are no side plates, as distinguished from the fins, but a top plate 63 is connected directly to the tops of the fins. The output connection 64 extends at right angles to, rather than generally in line with, the cathode leads which are here shown enclosed in a protecting thimble 65. The output tube 64 is intersected by a wave guide device 66 and provided with tuning extension 67 therebeyond.

In order to efficiently and economically enclose such an object in a light-weight container I, in this instance, also desirably form the six parts of said container of corrugated cardboard, although I do not wish to be limited to this material.

Part #1 of the container, generally designated by the reference character 68, is formed from a flat rectangular piece 69 of preferably corrugated cardboard by bending it at right angles to a central panel 70, providing side panels 71 and 72, and then bending the end pieces toward one another, through more than right angles, to provide right top panel 73 and left top panel 14, the latter being notched as indicated at 75 and 76 to respectively receive the threaded enlargement 77 on the wave guide 66 and the flange portions 78 on the output tube 64. The right top panel 73 is provided with a rectangular slot 79, desirably cut out prior to bending, to receive the cooling fins 62 of the magnetron, forming the primary member of a cradle therefor, allowing the lower ends of said fins to rest on the bottom panel 70, while preventing shifting by the engagement of the sides of the end fins and lateral edges of all of the fins, with the edges of the panel portion defining said slot 79.

Part #2 of the container 68 somewhat resembles part #3 of the container 20 of the first embodiment, in that it is formed from a rectangular piece of preferably corrugated cardboard 80 by bending end portions at right angles upwardly to leave center panel 81 and form side panels 82. It is then bent inwardly at right angles to provide shoulder or top portions 83 and 84, adapted to support the top plate 63, leaving a space therebetween to snugly receive output portions of the magnetron, forming the secondary member of a cradle therefor, then downwardly at right angles to provide inner side panels 85 and 86. The panel 86 is discontinued at a point where its lower edge, when assembled, just engages the tops of the panels 73 and 14 of the part #1, while the panels 83 and 85 are cut away to accommodate the wave guide 66, or so that the left hand edge of the panel 85, as viewed in Fig. 2^a, snugly

engages the right side of said wave guide when the parts are assembled. The lower portion of the panel 85 is bent at right angles outwardly, so that the outer edge of the end portion 87 engages the inner side of panel 82 from which it extends, thereby holding panel 85 spaced from panel 82 so that the former snugly engages the adjacent side of the flange portions 18.

Part #3 of the present embodiment of my container corresponds to some extent with the lower portion of part #5 of the container of the first embodiment, in that it is a rectangular preferably corrugated cardboard box device 88, open at top and bottom and telescoped over part #2 and parts associated therewith. The present part #3 is formed from a rectangular piece of material by bending four panels thereof into right angular relationship and securing the opposite ends together, as by means of glued cloth 89.

Part #4, illustrated in Fig. 3^a, of my present container, corresponds somewhat with part #4 of the first embodiment, except that it does not wrap around assembled parts #1, #2 and #3 and the object enclosed thereby, but instead serves as means resting on the top of part #2 and the plate 63 of the magnetron 60, to hold the latter against upward shifting from the cradle provided by parts #1 and #2. It is formed from a rectangular preferably corrugated cardboard member 90 bent at right angles from a central panel 91 thereof to provide end panels 92 and 93, again bent at right angles to provide complementing side panels 94 and 95, and then bent at right angles to provide intermediate normally-engaging panels 96 and 97, and again bent at right angles to provide panels 98 and 99, normally lying flat on the inner surface of the center panel 91. It provides, in effect, two box like portions of unequal size, both open at top and bottom. The lower edges of the panels 96 and 97 are desirably notched, as indicated at 101 and 102, to snugly receive the top plate 63 of the magnetron. In plan, it is like part #3, except that it has intermediate panels 96 and 97 and inner panels 98 and 99.

After fitting part #4 on top of the assembled magnetron in parts #1, 2 and 3; part #5, formed as a preferably corrugated box device 103 open at top and bottom, is telescoped over part #4 and then over part #3 with the parts enclosed thereby. Part #5 is formed from a rectangular piece of material by bending four panels thereof into right angular relationship and securing the opposite ends together as by means of glued cloth 104.

Part #6, illustrated fragmentarily in Fig. 3^a, is also a rectangular preferably corrugated cardboard box 105, formed generally like the box 104 and held in position after bending its panels into right angular relationship by a strip of glued cloth 106, but with a pair of opposite ends, rather than the top and bottom, open. The area of each open end corresponds to the area of each end panel 107 and 108 of part #5, so that part #6 is snugly telescoped over part #5 and the associated parts, completing the enclosure of the magnetron.

A consideration of Figs. 4^a and 5^a will show that the magnetron 60 illustrated is completely enclosed in the six parts, while having no part engaging the outer part #6. There is considerable air space between the cylindrical body portion 61 and all sides of the container, and two or three thicknesses of corrugated cardboard between the radiating fins 62 and the outer surface

of the container. All sides of the container, except the top, involve more than one thickness of corrugated cardboard, and the top wall is reinforced by the panels 96 and 97 which extend from the top of the magnetron plate 63 to engage the under-surface thereof.

It will also be seen that by virtue of the slots and notches, which respectively receive the fins 62, the threaded enlargement 78 of the output portion 64, as well as the engagement between panel 85 and said enlargement 78, and panel 86 and the outer face of the wave guide enlargement 77, undesirable shifting of the magnetron in the assembled container in any direction is effectively prevented.

Referring now to the embodiment of my invention illustrated in Figs. 1^b to 5^b, inclusive, there is shown a magnetron 110 comprising a generally cylindrical body or anode portion 111 from which fins 112 project for cooling purposes, side plates 113 which are generally annular, except for notches 114 where the cathode leads extend into the body portion, and generally rectangular extensions 115 secured to connecting top plate 116. In the present embodiment the output connection, here shown enclosed in a wooden protector 117, extends at right angles to, rather than generally in line with, the cathode leads, which are shown enclosed in a protecting thimble 118.

In order to efficiently and economically enclose such an object in a light weight container, I, in this instance, also desirably form the six main parts or units of said container of corrugated cardboard, although I do not wish to be limited to this material.

Part or unit #1 of the container, generally designated by the reference character 119, is formed from a flat rectangular piece 121 of preferably corrugated cardboard, by preferably slotting it while flat and bending it into hollow triangular prism form, that is, to provide a left hand normally sloping portion 122 and a right hand normally sloping portion 123, with a slot 124 defined by said portions for receiving the body portion 111 and finned and side plate portions 112 and 113 of the magnetron 110, forming the primary member of a cradle therefor. The sloping portion 123 provides a stop for the plate 116 and the sloping portion 122 provides a stop for the output portion protector 117.

The end of the sloping portion 122 is then bent under to provide a base portion 125, then bent back to provide a stiffening panel 126, engageable by the fins 112 and side plates 113 and normally lying at right angles to the sloping panel 122, and finally bent outward at right angles to said panel 126 to provide an underlying panel 127, reinforcing the sloping panel 122. The end of the sloping panel 123 is bent in a similar manner to provide base portion 128, complementary with respect to base portion 125, reinforcing panel 129 for the sloping panel 123, and which is also engageable by the fins 112 and side plates 113 of the magnetron 110 to assist in the support thereof, and underlying reinforcing panel 131 for the sloping panel 123.

The panel 129 is, in turn, desirably reinforced by a piece of corrugated cardboard 132 comprising angularly disposed portions 133 and 134, portion 133 of which underlies the panel 129 and the portion 134 of which serves as a brace between the panel 129 and the lower edge portion of the panel 131 at the vertex where the panels 123 and 128 unite. Lateral shifting of the magnetron is

desirably further guarded against by coil inserts 135 of corrugated cardboard disposed between each end of the body portion 111 and associated end plate 113 and the lateral edges of the panels 122, 123, 126 and 129. All the elements of part #1 are held in shape in any desired manner as by means of a piece of scotch tape 136 connecting complementary bottom panels 125 and 128.

One of the important advantages of the cradle, just described, of the container 119 is that the magnetron 110 is placed at such an angle that the preferably wooden protective tube 117, desirably screwed on the threaded enlargement at the base of the output lead, may be removed without taking the magnetron from the cradle, and the magnetron may be tilted, or rotated about the axis of its body 111, in order to facilitate connecting, or during the connection of, the necessary plumbing to the output lead after removal of said protective tube 117, while the cradle acts as a jig for the purpose.

Part #2 of the container 119 is similar to part #4 of the container 20 of the first embodiment, except that it lacks overlying top portions. It preferably consists of a rectangular corrugated cardboard member 137 which is placed beneath part #1 and the end portions bent upward at right angles around it, forming a U-shaped enclosing secondary member of a cradle for the magnetron 110, by being provided with sides 138 and 139.

Part #3 of the container 119 corresponds closely with part #3 of the container 68 of the second embodiment of my invention in that it is a rectangular, preferably corrugated cardboard box device 141, open at top and bottom, and telescoped over part #2 and parts associated therewith. It is formed from a rectangular piece of material by bending four panels thereof into right angular relationship, and securing the opposite ends together as by means of glued cloth 142.

Part #4, illustrated in Fig. 3^b, is formed in a manner identical with part #4 of the preceding embodiment, except that the sections thereof do not correspond in size therewith. It is formed from a rectangular preferably corrugated cardboard member 143, bent at right angles from a central panel 144 thereof to provide end panels 145 and 146, again bent at right angles to provide complementary side panels 147 and 148, then bent at right angles to provide intermediate normally engaging panels 149 and 151, and again bent at right angles to provide panels 152 and 153 normally lying flat on the inner surface of the central panel 144. Panel 153 is provided with a notch 150 to interlockingly receive an end portion of the peak of part #1 at the junction of the sloping panels 122 and 123. It provides, in effect, two boxlike portions of unequal size both open at top and bottom.

The lower edges of the panels 149 and 151, when assembled, snugly engage the fins 112 and side plates 113 of the magnetron and lie between the top plate 116 and the output protector 117, as shown most clearly in Fig. 4^b. In plan, it is like part #3 except that it has intermediate panels 149 and 151 and inner panels 152 and 153.

After fitting part #4 on top of the assembled magnetron in parts #1, 2 and 3, part #5, formed as a preferably corrugated box like device 154 open at top and bottom, is telescoped over part #4 and then over part #3 with the parts enclosed thereby. Part #5 is formed from a rectangular piece of material by bending four panels thereof

into right angular relationship and securing the opposite ends together as by means of glued cloth 155.

Part #6, also illustrated in Fig. 3^b, is a rectangular preferably corrugated cardboard piece 156, formed generally like the box 154 and held in position after bending its panels into right angular relationship as by means of a strip of glued cloth 157, but with a pair of opposite ends, rather than the top and bottom, open. The area of each open end corresponds with the area of each end panel 158 and 159 of part #5 so that part #6 is snugly telescoped over part #5 and associated parts, completing the enclosure of the magnetron.

A consideration of Figs. 4^b and 5^b will show that the magnetron 110, illustrated, is completely enclosed in the six main parts, while having no part thereof engaging the outer part #6. There is considerable air space between the cylindrical body portion 111, the associated fins and side plates 112 and 113, and all sides of the container and two or more thicknesses of corrugated cardboard lie between the radiating fins and plates and the outer surface of the container. All sides of the container, except the top, involve two or more thicknesses of corrugated cardboard, and the top wall is reinforced by panels 149 and 151 which extend from the magnetron fins 112 and end plates 113 to engage the undersurface thereof.

It will also be seen that by virtue of the slot 124, parts auxiliary to main part #1, and the panels 149 and 151, undesirable shifting of the magnetron in the assembled container in any direction is effectively prevented.

From the foregoing disclosure, it will be seen that I have shown how to economically and effectively form shipping containers for irregular objects, three examples of such objects being given, one a magnetron with oppositely extending projections in which the projections normally lie horizontal, another a magnetron with projections extending at right angles to one another and in which one of said projections is normally horizontal and the other vertical, and also a magnetron in which right angle projections are both normally inclined. In all forms of my invention the magnetron is exposable, for examination from the top, by removing one or more of the outer container members (one in the case of the first form, and three in the case of the other two forms) while still safely held in a supporting cradle.

Although preferred embodiments of my invention have been disclosed, it will be understood that modifications may be made within the spirit and scope of the appended claims.

I claim:

1. In combination, a container, a magnetron enclosed therein and consisting of a body generally cylindrical and from which projects an output lead and cathode leads at opposite ends, respectively, radiating fins, side plates the upper portions of which are rectangular and connected by a supporting top plate; said container comprising; first, a U-shaped member embracing the body, with its sides engaging said side plates, and on which the top plate rests; second, a base member having an upwardly opening slot receiving said U-shaped member; third, a side wrapping member having panels snugly engaging the sides of the U-shaped member and the top of the base member; fourth, an end wrapping member closing said side wrapping member; fifth, a top and bottom opening box member telescoping verti-

cally over the afore-mentioned assembled members; and sixth, an outer box member open at its ends and telescoping laterally over the assembled magnetron-containing five members.

2. In combination, a container, a magnetron enclosed therein and consisting of a body generally cylindrical and from which projects an output lead and cathode leads at opposite ends, respectively, radiating fins, side plates the upper portions of which are rectangular and connected by a supporting top plate; said container comprising; first, a corrugated cardboard U-shaped member embracing the body, with its sides engaging said side plates, and on which the top plate rests; second, a base member comprising a corrugated cardboard device with a top panel having a slot receiving said U-shaped member and supported on box shaped portions at its ends; third, a side wrapping member of corrugated cardboard having panels snugly engaging the sides of the U-shaped member and the top of the base member, and a bottom panel supporting said box shaped portions; fourth, an end wrapping member of corrugated cardboard closing said side wrapping member and with its ends engaging the ends of said top plate; fifth, a top-and-bottom-opening corrugated cardboard box member telescoping vertically over the aforementioned assembled members; and sixth, an outer corrugated cardboard box member open at its ends and telescoping laterally over the assembled magnetron-containing five members.

3. In combination, a container, a magnetron enclosed therein and comprising a body generally cylindrical and from which projects an output lead and cathode leads respectively, radiating fins, and an upper plate connected to said fins; said container comprising; first, a member bent to provide a bottom panel and overlapping top panels supporting said magnetron body; second, a side wrapping member having panels snugly engaging said magnetron body, a portion of said output projection, and the top surfaces of the top panels of the first-mentioned container member; third, a top and bottom opening box member telescoping vertically over the afore-mentioned assembled members; fourth, a double box-like member forming a spacing device for disposition between the magnetron plate and the upper wall of the container; fifth, a top and bottom opening box member telescoping vertically over the afore-mentioned assembled members; and sixth, an outer box member open at its ends and telescoping over the assembled five container members.

4. In combination, a container, a magnetron enclosed therein and comprising a body generally cylindrical and from which projects an output lead, wave guide, and cathode leads respectively, radiating fins, and an upper plate connected to said fins; said container comprising; first, a corrugated cardboard member bent to provide a supporting bottom panel and overlapping top panels, one of said top panels being slotted to receive portions of said fins and the other notched to receive portions of the output lead; second, a side wrapping corrugated cardboard member having panels snugly engaging said magnetron body, a portion of said output projection, and the top surfaces of the top panels of the first-mentioned container member and some of said panel portions being cut away to accommodate said wave guide; third, a top and bottom opening corrugated cardboard box mem-

ber telescoping vertically over the afore-mentioned assembled members; fourth, a double corrugated cardboard box-like member forming a spacing device for disposition between the magnetron plate and the upper wall of the container; fifth, a top and bottom opening corrugated cardboard box member telescoping vertically over the aforementioned assembled members; and sixth, an outer corrugated cardboard box member open at its ends and telescoping over the assembled five container members.

5. In combination, a container, a magnetron enclosed therein and comprising a body generally cylindrical and from which projects an output lead and cathode leads, respectively, radiating fins, side plates, to projections from which is connected an upper plate, and a protector on the output lead said container comprising; first, a member bent to provide a hollow triangular prism supporting device, with its top notched to form a receiving socket for the body of the magnetron, and sides sloping from an upper vertex to its ends and providing stops, respectively, for said protector and said upper plate; second, an end wrapping member on which the first part and the associated magnetron rests, said member being formed U shape to provide upstanding embracing arms at the ends of said first mentioned member; third, a top and bottom opening box member telescoping vertically over the aforementioned assembled members; fourth, a double box-like member having an intermediate spacing web for disposition between the magnetron fins and the upper portion of the container; fifth, a top and bottom opening box member telescoping vertically over the aforementioned assembled members; and sixth, an outer box member open at its ends and telescoping over the assembled five container members.

6. In combination, a container, a magnetron enclosed therein and comprising a body generally cylindrical and from which projects an output lead and cathode leads, respectively, radiating fins, and side plates, to projections from which is connected an upper plate, and a protector on the output lead, said container comprising; first, a member bent to provide a hollow triangular prism corrugated cardboard supporting device, with its top notched and forming a socket receiving the body of the magnetron, and sides sloping from an upper vertex to its ends and providing stops, respectively, for said protector and said upper plate, corrugated cardboard rigidifying means engaging the lower faces of the sloping upper sides to strengthen the same and assist in preventing shifting of said magnetron; second, an end wrapping corrugated cardboard member on which the first part and the associated magnetron rests, said member being formed U shape to provide upstanding embracing arms at the ends of said first mentioned member; third, a top and bottom opening corrugated cardboard box member telescoping vertically over the aforementioned assembled members; fourth, a corrugated cardboard double box-like member having an intermediate spacing web for disposition between the magnetron fins and the upper portion of the container; fifth, a top and bottom opening corrugated cardboard box member telescoping vertically over the aforementioned assembled members; and sixth, an outer corrugated cardboard box member open at its ends and telescoping over the assembled five container members.

7. The method of wrapping an irregular object for shipment, comprising taking six pieces of flat corrugated cardboard, slotting the first of said pieces while flat to receive the body of said object and, with the second of said pieces, making a cradle, supporting said object on said cradle, bending the third of said pieces into panels in right angular relationship, telescoping said bent piece over said cradle to partially close it, bending the fourth of said pieces at right angles from a central panel to form end panels, bending said end panels at right angles to form panels extending toward one another from said end panels, placing said formed piece around at least a portion of the cradled and partially enclosed object so that edge portions thereof snugly engage the body of the object, thereby preventing shifting thereof in said cradle, making open-ended complementary telescoping box members of the fifth and sixth pieces, fitting one of said box members over the cradled object and associated first four pieces, and placing the other box member over said fitted first-mentioned box member, so that said box members supplement one another and form a complete outer wrapper.

8. In combination, a container, an object enclosed therein and having a body portion and a plurality of lateral projections each extending longitudinally outward in a direction different from that of another projection from about the center of the body portion, said container comprising a cradle device including a primary member providing a socket holding said body portion snugly against contact with the container outer walls, with the projections not enclosed but extending outwardly of said primary member, and preventing displacement of said projections, a secondary member embracing said primary member and completing said cradle device, and an outer closure comprising a box member open at its opposite ends and in which said cradle device fits telescopically, and an outer box open at its opposite ends and in which said box member fits telescopically, so as to cover its open ends and form a complete closure for the object.

9. In combination, a container, a magnetron enclosed therein and consisting of a body portion generally cylindrical with radiating fins and side plates, and from which projects an output lead and cathode leads, respectively, said container comprising a corrugated cardboard cradle device including a primary member providing a socket holding said body snugly against contact with the container outer walls, with the output lead and cathode leads not enclosed by but extending outwardly of said primary member and preventing displacement of said leads, a secondary member embracing said primary member and completing said cradle device, and a two-piece outer closure comprising a corrugated cardboard box member open at its opposite ends and in which the cradle device is telescoped and an outer corrugated cardboard box open at its opposite ends and in which said box member fits telescopically so as to cover its open ends, and forming a complete closure for the magnetron, while, after removing said two-piece outer closure, permitting removal of the magnetron from said cradle device by bodily lifting it thereout without unscrewing or untwisting any parts.

10. The method of wrapping an irregular object for shipment, comprising taking six pieces of flat corrugated cardboard, slotting the first of said pieces while flat to receive the body of said object and, with the second of said pieces, making

13

a cradle, supporting said object on said cradle, bending the third of said pieces into panels in right angular relationship, telescoping said bent piece over said cradle to partially close it, bending the fourth of said pieces at right angles from a central panel to form end panels, bending said end panels at right angles to form panels opposite said central panel, bending said opposite panels at right angles to form panels extending into engagement with said central panel, placing 10 said formed piece around at least a portion of the cradled and partially enclosed object so that edge portions thereof snugly engage the body of the object, thereby preventing shifting thereof in said cradle, making open-ended complementary telescoping box members of the fifth and sixth pieces, fitting one of said box members over the cradled object and associated first four pieces, and placing the other box member over said fitted first-mentioned box member, so that said box 20

5

members supplement one another and form a complete outer wrapper.

HAROLD AMATEL.
